R. P. YOUNG.
REFILLABLE FUSE.

APPLICATION FILED APR. 13, 1917. RENEWED OCT. 9, 1919.

1,359,561.

Patented Nov. 23, 1920.

Inventor

Robert P. Young.

By William C. Linton.
Attorney

UNITED STATES PATENT OFFICE.

ROBERT PEARCE YOUNG, OF MONTREAL, QUEBEC, CANADA, ASSIGNOR TO WILFRID TAIT, OF MONTREAL, CANADA.

REFILLABLE FUSE.

1,359,561.

Specification of Letters Patent. Patented Nov. 23, 1920.

Application filed April 13, 1917, Serial No. 161,693. Renewed October 9, 1919. Serial No. 339,841.

To all whom it may concern:

Be it known that I, ROBERT P. YOUNG, a subject of the King of Great Britain, residing at Montreal, Province of Quebec, Canada, have invented certain new and useful Improvements in Refillable Fuses; and I do hereby declare that the following is a full, clear, and exact description of the invention, such as will enable others skilled in the art 10 to which it appertains to make and use the same.

The present invention relates to fuses and an object of the present invention is to provide a casing or holder for fuses which may 15 be readily assembled or disassembled in placing and removing the fusible wires therefrom.

With the above and other objects in view which will hereinafter appear as the description continues, the invention consists of the novel features of construction, combination and formation of parts as will be hereinafter more fully described and particularly pointed out in the appended claims.

25 In the accompanying drawings:

Figure 1 is a vertical longitudinal section through the fuse embodying the present invention;

Fig. 2 is a cross section through the same 30 taken on the line 2—2 of Fig. 1;

Fig. 3 is a disassembled perspective view of the casing; and,

Fig. 4 is a detail perspective view of the cover for the casing.

35 The invention will be best understood from a consideration of the following detailed description, taken in connection with the accompanying drawings forming part of this specification, with the further understanding that while the drawings show a 40 partial form of the invention, the latter is not confined to any strict conformity with the showing of the drawings, but may be changed and modified so long as such 45 changes and modifications mark no material departure from the salient features of the invention.

Like and corresponding parts are indicated by similar reference characters throughout 50 the several views.

The casing comprises an elongated tube 1 of preferably cylindrical configuration having its opposite ends opened and being preferably made of fiber, but, of course, it can 55 be made of any other suitable insulating

material. A longitudinal slot is formed throughout the entire length of this casing 1 in which is adapted to rest a segmental cover plate 2 being made of the same material as the body portion 1 of the casing. Secured 60 to the inner face of the cover plate 2 is a mica sheet 3 preferably arcuate in cross section having its opposite sides projecting beyond the cover plate 2 and these projections are adapted to rest within the casing 1 for 65 securing the cover plate in place. In placing the cover plate upon the casing the same is inserted at one end thereof and moved along until the ends of the cover lie flush with the ends of the casing and the mica 70 plate 3 prevents the cover plate from being withdrawn. The opposite ends of the casing are adapted to be closed and incased by means of the caps 4 preferably made of brass. Secured to the opposite ends of the 75 cover plate 2 by means of the bolts 5 are the brackets 6. The shank portions of these bolts 5 project beyond the cover plate and are provided with the nuts 7. The caps 4 are provided with the slots 8 for receiving the 80 shank portions of the bolts 5, thereby preventing the caps from being rotated upon the casing 1. Extending through the medial portion of the caps 4 and adapted to be brought into threaded engagement with the 85 brackets 6 are the set screws 9. When the cover plate is inserted into position, the caps are placed upon the ends of the casing and the set screws 9 secured in position the caps will be prevented from being removed and 90 the cover plate locked in position. The bolts 5 also secure the brackets 6 upon the cover plate 2 and each of the shank portions of these bolts are provided with openings 95 through which project the opposite ends of the fuse wire 10 and these bolts 5 are provided with T ends which are adapted to rest upon the opposite ends of the wire 10 for securely locking the same into position.

From the foregoing it is obvious that by 100 providing a sectional casing such as described, the same may be readily assembled or disassembled so that the fuse wire 10 may be replaced thereby increasing the life of the fuse. When the fuse has been assembled as 105 shown in Fig. 1 and it is desired to replace the fusible wire 10 one of the set screws 9 and a cap 4 may be removed and the cover plate 110 slidably removed from the casing, thereby presenting the fuse wire to ready access so

that it may be removed and a new one substituted therefor. The cover plate may then again be inserted in place and the set screws tightened so as to connect one of the caps 5 to one of the brackets 6, thereby securely locking the same into position and again presenting the fuse for use.

Having thus fully described my invention, what I claim as new and desire to set 10 cure by Letters Patent is:

1. A fuse comprising a casing, a longitudinally slidable member arranged in said casing and forming a part thereof, means for connecting said slidable member to said 15 casing and a fuse wire detachably connected to said slidable member.

2. A fuse comprising a casing, a plate slidably mounted in said casing and forming a section thereof, means for connecting 20 said plate to said casing and a fuse wire detachably connected to said plate.

3. A fuse comprising a casing, a longitudinally slidable element adapted for location within said casing, and closing one side 25 thereof, means connected to said slidable element for retaining the latter within said casing and a fuse wire detachably connected to said slidable element.

4. A fuse comprising a tubular casing, a 30 longitudinally slidable member connected to said casing and closing one side thereof, brackets secured to said member, means for detachably connecting said member to said casing, a fuse wire detachably connected to 35 said brackets and means for securing said brackets to said slidable member.

5. A device of the class described comprising an elongated casing, a longitudinally slidable segmental member connected 40 to said casing and forming a side closure therefor, brackets secured to said segmental member, a fuse wire detachably connected to said brackets, end caps for inclosing the opposite ends of said casing and segmental member and means whereby upon the removal of one of said end caps, the said segmental member may be adjusted to expose said fuse.

6. A device of the class described comprising a tubular casing, a segmental member adjustably connected to said casing and forming a side closure therefor, brackets secured to the opposite ends of said segmental member, a fuse detachably connected to 50 said brackets, caps inclosing the ends of said casing and adapted for preventing the movement of said adjustable member, and means whereby upon the removal of one of said caps, the said segmental member may be adjusted to expose said fuse.

7. A device of the class described comprising a tubular casing, a segmental member capable of longitudinal adjustment within said casing and forming a closure 65 from one side thereof, brackets secured to

the opposite ends of said segmental member, a fuse detachably connected to said brackets, caps arranged upon the opposite ends of said casing and segmental member, means for connecting said brackets to the segmental member, means for securing the fuse to 70 said brackets, and means for detachably connecting said segmental member to said casing.

8. A device of the class described comprising a tubular casing, a segmental member capable of longitudinal adjustment within said casing and comprising a side portion thereof, brackets secured to the opposite ends of said segmental member, a fuse 75 detachably connected to said brackets, caps arranged upon the opposite ends of said casing and segmental member, means for connecting said brackets to the segmental member, means for securing the fuse to 80 said brackets, and means for detachably connecting said segmental member to said casing, and means whereby upon disconnection of one of said caps, the said segmental member may be withdrawn from said casing to expose said fuse.

9. A device of the class described comprising an elongated tubular casing having a longitudinal slot formed in one side extending the full length thereof, a longitudinally slidable cover adapted for arrangement in said casing slot, an insulating member connected to said cover, said member adapted for engagement with said casing for holding said cover within said casing 95 slot, brackets connected to said cover, a fuse wire detachably connected to said cover, and caps adapted to be placed over the opposite ends of said casing.

10. A device of the class described comprising a cylindrical casing having a slot formed therein, a cover adapted to rest within said slot, an insulating plate carried by said cover and adapted to rest within said casing for holding said cover there- 100 within, brackets secured to said cover, a fuse wire detachably connected to said brackets, and caps adapted to be placed over the opposite ends of said casing and cover.

11. A fuse comprising a cylindrical casing, said casing having a slot formed therein, a cover slidably mounted in said slot, an insulating plate carried by said cover and adapted to hold said cover within said casing, a pair of T bolts secured to said cover, 115 brackets connected to said cover, a fusible wire detachably connected to said T bolts, end caps for inclosing the opposite ends of said casing and cover, and means for detachably connecting said end caps to said 120 brackets.

12. A fuse of the character described comprising a cylindrical casing, said casing having a slot formed therein and extending throughout its length, a cover adapted to 130

rest within said slot, a mica plate carried by said cover and adapted to rest within said casing for retaining the cover within said slot, a fuse wire detachably connected to the inner face of said cover and caps adapted to be placed over the opposite ends of said cover and casing substantially as and for the purpose specified.

13. A fuse comprising a cylindrical casing, said casing having a slot formed therein and extending throughout its length, a cover being arcuate in cross section and adapted to rest within said slot, a mica plate secured to the inner face of said cover, the opposite sides of said mica plate pro-

jecting beyond said cover, the projecting sides of said mica plate adapted to rest within said casing for retaining the cover within said slot, a pair of T bolts secured to said cover, brackets carried by said cover, a fusible wire detachably connected to said T bolts, and caps for inclosing the opposite ends of said casing and cover and means for detachably connecting said end caps to said brackets substantially as and for the purpose specified.

In witness whereof I have hereunto set my hand.

ROBERT PEARTE YOUNG.
